UNITED STATES PATENT OFFICE

113,762

DESIGN FOR A COMBINED PORTABLE AIR CONDITIONER AND TABLE

Edwin W. Petersen, Detroit, Mich., assignor to
American Blower Corporation, Detroit, Mich.,
a corporation of Delaware

Application January 27, 1938, Serial No. 74,600

Term of patent 7 years

To all whom it may concern:

Be it known that I, Edwin W. Petersen, a citizen of the United States, residing at Detroit, in the county of Wayne and State of Michigan, have invented a new, original, and ornamental Design for a Combined Portable Air Conditioner and Table, of which the following is a specification, reference being had to the accompanying drawings, forming a part thereof.

In the drawings:

Figure 1 is a front elevational view of a combined portable air conditioner and table showing my new design in closed position;

Figure 2 is a front elevational view thereof

showing both front and rear doors in open position, the front door being shown in perspective;

Figure 3 is a top plan view thereof;

Figure 4 is a rear elevational view thereof with the narrow rear doors in open position; and

Figure 5 is a side elevational view thereof on a slightly reduced scale. The other side of the article is substantially plain.

I claim:

The ornamental design for a combined portable air conditioner and table, substantially as shown and described.

EDWIN W. PETERSEN.
